UNITED STATES PATENT OFFICE.

JESSE SNODGRASS, OF KENTON, OHIO.

GYNECOLOGICAL STIRRUP.

SPECIFICATION forming part of Letters Patent No. 564,947, dated July 28, 1896.

Application filed August 24, 1895. Serial No. 560,361. (No model.)

To all whom it may concern:

Be it known that I, JESSE SNODGRASS, a citizen of the United States, residing at Kenton, in the county of Hardin and State of Ohio, 5 have invented certain new and useful Improvements in Gynecological Stirrups, of which the following is a specification, reference being had therein to the accompanying drawings.

10 My invention relates to a gynecological stirrup, and it has for its object the production of a device which can be readily applied to and disengaged from a table, bedstead, and the like, which will permit of any desired horizontal or vertical adjustment of the stirrup proper in its holder, and which can be conveniently carried in the surgeon's instrument-case.

15 The invention will first be described in connection with the accompanying drawings, and then pointed out in the claim.

Figure 1 of the accompanying drawings is a perspective view illustrating the manner of attaching my stirrup to an operating-table. 20 Fig. 2 is a like view illustrating the stirrup attached to a bedstead. Fig. 3 is a longitudinal vertical sectional view of the stirrup and holder. Fig. 4 is a perspective view of the stirrup detached from its holder. Fig. 5 is a 25 perspective view of the holder.

30 Referring to the drawings, A represents the stirrup proper, which is shaped to receive the heel portion of the foot, as shown in various views, and formed integral with a shank 1 and a stem 2, the plane of the heel-receiving portion of the stirrup being at an obtuse angle to the shank and stem. The shank is made larger in cross-section than the stem, so as to leave a shoulder 3 for limiting the inward 35 adjustment of the stirrup in its holder.

40 B represents the stirrup-holder, consisting of a clamp comprising three arms, a clamping-screw working in one of the arms, and two binding-screws, of which one is carried by each of the other arms, all the arms being 45 formed integral. Arms b and b', which stand at a right angle to each other, are hollow, the bore 4 in each running longitudinally through the arm, as clearly shown in Fig. 3; and at 50 their intersection these arms are cut away at 5, so as to uncover the respective bores, this cut-away portion 5 forming a supporting-

shoulder for the shank 1 of the stirrup proper when the stirrup has been inwardly adjusted to its limit. Each of these arms carries a binding-screw 6, which passes through into the bore. Arm b² stands parallel with arm b, but is shorter. Through the free or outer end of arm b² is formed a screw-threaded opening 7, through which passes a clamping-screw 8, 55 which is provided with a swiveled head 9. This head, as well as the spurs 10, formed on the inner edge of arm b, may, if desired, be covered with rubber or other suitable material, so as to avoid marring the article to which the 60 holder may be attached.

By making arm b² shorter than arm b I economize in the weight of the device and also bring the clamping-screw in the best possible relation to the spurred arm to secure a 65 firm attachment of the holder.

70 From the foregoing description it will be observed that the stem of the stirrup can be inserted and adjustably secured in either of the arms b or b' of the holder, and that the 75 holder can be readily secured to either a horizontal or a vertical surface. Furthermore, the device, when not in use, can be taken apart and conveniently packed in the surgeon's instrument-case or satchel.

75 Having thus described my invention, what I claim as new, and desire to secure by Letters Patent, is—

In a gynecological stirrup, a stirrup-holder 80 comprising a spurred and longitudinally-bored arm, another longitudinally-bored arm at a right angle to the spurred arm, the bores extending throughout the length of these respective arms, said arms being cut away at their junction so as to uncover the respective 85 bores and each provided with a set-screw passing into the bore, a solid arm parallel with the spurred arm, and a clamping-screw 90 passed through the solid arm, in combination with a stirrup proper having a shouldered 95 stem adapted to be adjustably secured in either of the bored arms.

In testimony whereof I affix my signature in presence of two witnesses.

JESSE SNODGRASS.
